UNITED STATES PATENT OFFICE.

WILLIAM J. ROA, OF ST. LOUIS, MISSOURI, ASSIGNOR TO AMERICAN CAR AND FOUNDRY COMPANY, OF NEW YORK, N. Y., A CORPORATION OF NEW JERSEY.

GENERAL-SERVICE RAILWAY CAR.

Application filed August 29, 1922. Serial No. 585,034.

To all whom it may concern:

Be it known that I, WILLIAM J. ROA, residing at St. Louis, State of Missouri, and being a citizen of the United States, have invented certain new and useful Improvements in a General-Service Railway Car, of which the following is a full, clear, and exact description, such as will enable others skilled in the art to which it appertains to make and use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is an elevation of a fragmentary portion of a dumping car showing a drop door held closed by the improved locking device;

Figure 2 is a transverse section through said car portion and drop door taken on line 2—2 of Figure 1 looking in the direction indicated by the arrow, and showing the drop door positioned in a plane below the floor line of the car and held by the locking device;

Figure 3 is a horizontal sectional view through the car side above the door taken on line 3—3 of Figure 1 looking in the direction indicated by the arrow and showing a plan of the door locking mechanism mounted at the car side;

Figure 4 is a vertical section through one of the bearings securing the locking device to the car, and

Figure 5 is a view similar to Figure 2, but showing the door arranged flush with the car floor.

My invention relates to that class of dumping cars in which the floor comprises drop doors hinged to permit their free edges to drop away from the car side and adapted to be severally raised by hand.

It is an object of this invention to provide means for locking the several doors in their raised position, said means being adapted to severally release said doors.

A further object is to so arrange said locking mechanism as to permit the use of auxiliary devices to assist in the door raising operation.

In the drawings, 10 represents the center

sills of the car, 11 the car side, 12 the car floor, and 13 designates one of the drop doors forming part of the floor area. The doors 13 are shown hinged to the center sills 10 with their free edges arranged near the car side. Each door is raised by hand and is locked in closed position and released by means of a shaft 14 extending adjacent the free edge thereof and mounted on the car side above the door level.

The shafts 14 are each provided intermediate their ends with a plurality of spaced stirrups 15 formed preferably by bending the shaft 14 as shown in Figure 1, the unbent portions of the shaft being journaled in brackets 16 secured to the car side above the door. The stirrups 15 extend below the level of the door and are positioned to receive the door supporting and stiffener arms 17 secured to the underside of the door and extending beyond the free edge thereof and beyond the adjacent car side.

Due to the possible distortion of the door under conditions involving severe service the door may not completely close the discharge opening in the car floor resulting from the failure of one of the door stiffener arms 17 to properly seat itself within adjacent stirrup 15 when the door is raised. To insure complete closure thereof the stirrups 15 are shaped as at 18 to provide ample room at one side of the door stiffener arm 17 to accommodate an auxiliary door lifting hand bar (not shown) for thrusting the respective side of the door to final closed position. Each door, inwardly from the free edge thereof, is furnished with a loop piece 19 secured to the underside of the door between the door stiffeners 17 and between the stirrups 15 of the locking shaft to accommodate the door lifting bar during the initial door raising operation.

Fixed to one extremity of the locking shaft 14 is an operating handle 20 held against movement within a keeper 21 secured to the car at a point below the door level. The keeper supports a latch plate 22 pivotally mounted to move in a horizontal plane to a position into and out of the path of movement of operating handle 20. The latch plate is held in its handle locking position by pin 23 taking the keeper and latch plate.

To release a door, locking pin 23 is withdrawn and latch plate 22 moved to a position out of the path of handle 20 as indi-

cated in broken lines in Figure 3 and the handle moved outwardly and upwardly from the car to force the stirrups 15 away from their supporting positions under the 5 door as indicated in broken lines of this figure whereupon the door will drop to discharge its lading.

To raise a door all that is necessary is to grasp the door and lift same to a position

10 high enough to permit door stiffener arms 17 to enter their respective stirrups 15, using the auxiliary bar hereinbefore referred to, if necessary. When the doors have been raised to their final closed position, handle

15 20 of the locking device will again be lodged within its keeper 21, the latch plate will then be returned to its handle retaining position indicated in full lines in the drawings and held against displacement by pin 23.

20 The locking shaft may be detachably mounted as shown in the drawings. It has no permanent connection with the door and does not operate to lift the door from its dumping position but functions independently of door movement, namely, prior to the dropping of the door and after it has been raised.

25 Since there is no binding connection between the locking shaft and the door, the shaft may be readily mounted upon and removed from the car. The shaft journal brackets 16 devised as shown will greatly facilitate the assembling and dismantling operations. The brackets 16 comprise a base 30 plate 25 fixedly secured to the car by countersunk rivet 26 or the like. The base plate is provided with a shaft bearing portion 27 and a socket portion 28 to accommodate a complementary piece 29 having a portion 30 adapted to interlock with the socket 28 on the base plate. Part 29 has a shaft bearing portion 31 by means of which and bearing portion 27 of the base plate, shaft 14 is supported, all of said parts being held in operative relation by a removable bolt 32 connecting the whole to the car frame.

35 It will be noted that each door forming part of the car floor of a dumping car is provided with a locking device having no connection with any other door or door locking device on said car. Each door is supported directly upon shafts journaled in a plane above the normal level of the door and engages said shaft at points adjacent 40 the sides of said door and intermediate the shaft journal brackets 16.

45 Although the weight on the doors is concentrated on the stirrups of the locking shaft, the relative arrangement of the stirrups on the shaft and the shaft journal brackets 16 results in a further distribution of the load to the car over a space corresponding to the length of said locking shaft.

50 What I claim is:

55 1. In a general service railway car having

side walls and a floor, a plurality of manually operable drop doors forming part of the floor area of the car and hinged with their free edges adjacent the car sides, manually and severally operable door supporting 70 shafts rotatably mounted on the side walls above the free edges of said doors when closed, said shafts being operable independently to release said doors.

2. The combination comprising a general 75 service railway car having a manually operable drop door and a side wall, a supporting shaft on the side wall adjacent the free edge of said door shaped to provide spaced stirrup portions extending above and below the free edge of the door when raised, and shaft journal brackets on the car above said door and on opposite sides of said stirrup portions.

80 3. In a general service railway car having side walls and a plurality of manually and severally operable drop doors, forming part of the floor between said walls and hinged with their free edges adjacent the car sides, independently operable door supporting shafts, and a plurality of brackets on the side walls for rotatably supporting said shafts above said doors.

85 4. The combination comprising a general service railway car having a manually operable drop door and a side wall, a locking shaft on the car wall above the door when closed and having a plurality of door supporting stirrups intermediate its ends, and a plurality of shaft supporting brackets on 90 said wall on opposite sides of said stirrups.

95 5. In a general service railway car having side walls and a plurality of manually and severally operable drop doors forming part of the floor between said walls, door supporting shafts on the side wall adjacent the free edges of said doors shaped to provide spaced stirrup portions intermediate their ends, and shaft supporting brackets on the car intermediate said stirrup portions, said 100 shafts being independently operable to severally release said doors.

105 6. In a general service railway car having a manually operable drop door and a side wall, a door supporting shaft on the side wall adjacent the free edge of said door shaped to provide spaced stirrup portions intermediate its ends and an operating handle at one extremity thereof, shaft supporting brackets on the car on opposite sides of 110 said stirrup portions, and a keeper on the car adapted to receive said operating handle to prevent rotation of said shaft.

115 In witness whereof I have hereunto set my hand in the presence of two witnesses.

WILLIAM J. ROA.
